HAIR DRIER

Andrew List and Charles Sanford Stuart, Regina,
Saskatchewan, CanadaApplication March 1, 1934, Serial No. 713,586
In Canada August 30, 1933

6 Claims. (Cl. 34—26)

This invention relates to hair driers for use in drying a person's hair in beauty parlours and the like.

The main object of the invention is to provide a compact assembly of this character which will provide for the efficient drying of hair and which will avoid the disadvantage of having the hot air current blown down over the head and face of the person being treated.

10 A further object of the invention is to arrange for the removal of the warm air from the head area of the person being treated by simple and convenient means co-operating with the air impelling means of the drier.

15 A still further object of the invention is to provide an apparatus of this character which can be manufactured at a comparatively low figure.

With these and other objects in view the invention consists essentially of a casing enclosing a heating element and air impeller, the casing carrying a head piece or helmet, designed to fit over the head of the person being treated, and communicating with the interior of the casing so that air may be impelled from the casing into the head piece and into contact with the hair. Along with this construction is provided an air withdrawing channel which is built on the casing and communicates with the top of the head piece, the channel communicating with the fan end of the casing, and thereby under the influence of the air impeller so that air impelled into the head piece, after contact with the hair, is withdrawn under the force of the one impeller, as more fully described in the following specification and illustrated in the accompanying drawing which forms part of the same.

In the drawing:

Figure 1 represents a side elevation of the hair drier.

40 Figure 2 is a rear end view of Fig. 1, and

Figure 3 is a view similar to Fig. 1 showing the casing and related parts in section.

Referring more particularly to the drawing, A 45 indicates the hair drying apparatus as a whole which comprises a casing 10 mounted upon a suitable base 11. The casing 10 forms a general air passageway 12 and houses the fan 13 and resistance heating elements 14 which are positioned in advance of the fan. The fan motor and resistance elements are connected in suitable electrical circuit so that, when closed, the fan will operate and the resistance elements will be heated whereby the current of air impelled by 50 the fan within the passageway 12 will pass by

the resistance elements to cause the air to be heated.

The air current is impelled toward the forward end of the casing which has mounted thereon in any suitable manner a head piece 15. This head piece is perforated or orificed as at 16 and its exterior wall 17 throughout is accessible to the air passing from passageway 12. In this connection it will be noted that the outer casing member 18 of the head piece is spaced from the outer surface 17 by the air channel 19 so that the air from the passageway 12 may be circulated completely around the sides of the head piece. In this way, therefore, when persons having their hair dried have the head piece mounted on their heads and over their hair, hot air is blown through the hair to dry it.

15 In many types of construction, however, the hot air blown through the hair has only one outlet, namely, down between the head piece and the head and thus it blows over the face of the person being treated. This results in a very disagreeable condition. In some cases provision has been made to avoid this difficulty but this has necessitated a more complicated form of apparatus.

20 In the present case, means have been provided for withdrawing this air from the head piece after it has passed through the hair so that it will not be impelled down over the face of the person being treated. This means is embodied in a simple form of apparatus requiring very little added construction and no additional apparatus for air withdrawal.

25 Upon referring to Figure 3 particularly, it will be seen that the top of the head piece is formed with a passageway or duct 20 which communicates with an air withdrawal channel 21, formed along the top of the casing and terminates at its rearward end, opening to the atmosphere. On 30 the rearward end of the casing 10 is provided a damper arrangement including a plurality of substantially segmental openings 22 which may be screened as at 23 and controlled by a suitable damper or valve member 24 operated from the 35 operating knob 25. It will be noted that the rear end of the casing which, as shown in Figure 3, is in the form of a closure cap 26 has three of the substantially segmental openings 22 spaced equi-distant while a fourth opening is 40 closed by a conduit member 27 which is provided with an extension or nozzle-like piece 28, designed to fit into the rearward opening of the channel 21 so that communication is established 45 between this channel and the rearward end of 50

55

passageway 12 behind the fan 13, consequently suction is established in passageway 21 and therefore hot air which is blown into the head piece 15 is thereafter removed through the passageway 21 and will not be propelled over the face of the person being treated.

In this way the apparatus provides for the removal of air from the head piece without the necessity of employing any additional suction apparatus while the construction, it will be noted, requires very little by way of addition to the conventional apparatus to effect this desired end. The arrangement is such that all the parts are compactly arranged so that the device may be built readily and produced at relatively low cost.

It will be apparent that any number of openings 22 may be employed in the end plate 26 or the end of the casing, while the openings 20 are provided with the screen 23 of suitable mesh to avoid dust particles and the like. In the passageway 20, screening 29 may be positioned, while within the passageway 12 a baffle member or air deflector 30 may be employed to direct the air currents more efficiently to all parts of the head piece.

Various modifications may be made in the invention without departing from the spirit thereof or the scope of the claims, and, therefore, the exact forms shown are to be taken as illustrative only and not in a limiting sense, and I desire that only such limitations shall be placed thereon as are imposed by the prior art or are specifically set forth in the appended claims.

We claim:—

1. A hair drying device comprising a casing enclosing an air passageway, an air impeller and heating element mounted within said passageway, a head piece mounted on the casing orificed over a major portion of its surface to communicate with said passageway, an air channel above said passageway extending between said head piece and passageway for removing hot air introduced to the head piece from the passageway, said air channel communicating with the suction side of the air impeller, and damper means in the end of the casing communicating with the atmosphere to regulate the supply of fresh air to said passageway.

2. A device as claimed in claim 1 in which the damper means include a plurality of openings in the rearward end of the casing, and a valve member for regulating the size of said openings.

3. A hair drying device comprising a casing enclosing an air passageway, an air impeller and

heating element mounted within said passageway, a head piece mounted on one end of the casing orificed to communicate with said passageway, an end plate closing the other end of the passageway, damper means in said end plate for introducing air into the passageway, and an air channel communicating with the head piece at one end and with the passageway through said end plate at the opposite end, said air channel communicating with the air passageway rearwardly of the impeller, whereby hot air introduced to said head piece by the impeller is withdrawn thereby.

4. A hair drying device comprising a casing enclosing an air passageway, an air impeller and heating element mounted within the said passageway, a head piece mounted on the casing orificed to communicate with said passageway, said head piece having a passageway in its top, an air channel opening to the atmosphere rearwardly of the casing, a conduit connecting the passageway at the top of the head piece with said air channel and a removable conduit connection between said air channel and the air passageway rearwardly of the impeller whereby hot air introduced to said head piece by the impeller is withdrawn thereby.

5. The device as claimed in claim 4 in which the rearward end of the casing is closed by an end plate and the conduit connection member is mounted on said end plate and insertable within said channel when the end plate is mounted on the casing.

6. A hair drying device comprising a casing enclosing an air passageway, an air impeller and heating element mounted within said passageway, a head piece mounted on the casing orificed to communicate with said passageway, the outer surface of said head piece being accessible to air currents impelled from said passageway, said head piece being formed with an opening, a conduit connected to the casing forming an air channel, said channel communicating with said opening, said air channel opening to the atmosphere at the rear of the casing, an end plate for the casing, said end plate having a screened opening to admit air to the casing, means in connection with said end plate for regulating the size of said opening, and conduit means extending between the air channel and end plate and communicating with said air passageway whereby hot air introduced to said head piece by the impeller is withdrawn.

ANDREW LIST.

CHARLES SANFORD STUART. 55
